SPOON OR SIMILAR ARTICLE

Robert S. Conland, Vernon, N.Y., assignor to
Oneida Ltd., Oneida, N.Y.

Filed Apr. 24, 1970, Ser. No. 22,618

Term of patent 14 years

Int. Cl. D7—03

U.S. Cl. D54—12

FIG. 1

FIG. 2

FIG. 3

FIG. 4

FIG. 5

FIG. 1 is a front view of a spoon showing my new design;

FIG. 2 is a rear view therof;

FIG. 3 is a side view thereof, the undisclosed side being substantially identical with the side shown in FIG. 3;

FIG. 4 is an enlarged cross-section taken on line 4—4 of FIG. 1; and

FIG. 5 is an enlarged cross-section taken on line 5—5 of FIG. 1.

The essential features of my design for a spoon or similar article reside in the configuration of the handle in combination with the particular type of ornamentation as applied thereto.

I claim:

The ornamental design for a spoon or similar article, substantially as shown and described.
